UNITED STATES PATENT OFFICE.

LOUIS W. GREVE, OF CLEVELAND, OHIO, ASSIGNOR, BY MESNE ASSIGNMENTS, TO THE CLEVELAND ROCK DRILL COMPANY, OF CLEVELAND, OHIO, A CORPORATION OF OHIO.

FLUID-OPERATED TOOL.

1,100,825.

Specification of Letters Patent. Patented June 23, 1914.

Application filed October 1, 1913. Serial No. 792,700.

To all whom it may concern:

Be it known that I, LOUIS W. GREVE, a citizen of the United States, residing at Cleveland, in the county of Cuyahoga and State of Ohio, have invented certain new and useful Improvements in Fluid-Operated Tools, of which the following is a specification.

The invention relates to fluid operated tools or machines, and particularly to fluid operated rock drills. The invention has for its primary objects; the provision of improved means controlled by the throttle valve whereby the movement of the hammer

15 piston is stopped while permitting the drill rotating mechanism to continue its operation; the provision of improved means for stopping and starting the actuation of the main controlling valve without stopping the 20 flow of air through the hollow drill steel; and the provision of improved means controlled by the throttle whereby the exhaust port is closed and all of the air supplied to the machine is directed through the hollow 25 drill steel when the operation of the main controlling valve and the hammer piston is stopped. One embodiment of the invention is shown in the accompanying drawings, wherein—

30 Fig. 1 is a longitudinal section with the operating parts thereof in one position, Fig. 2 is a similar longitudinal section through a portion of the machine, with the operating parts in another position, Fig. 3 is an enlarged section through the machine at the throttle valve, and Figs. 4, 5, and 6 are diagrammatic sectional views through the throttle valve showing it in its various positions.

40 Referring first to the general arrangement of parts as shown in Figs. 1, 2, and 3, 1 is the main cylinder of the machine carrying the hammer piston 2 and the anvil 3; 4 is the cylinder of the main or controlling valve 45 5; 6 is the throttle valve for controlling the admission of fluid to the apparatus; 7 is the drill steel angular in cross section and slidably but non-rotatably fitting the chuck 8; 9 is a transversely working piston for securing the step-by-step rotation of the chuck and the drill steel carried thereby; and 10 is a valve for controlling the movements of the piston 9.

50 The chuck 8 is operated by means of a ratchet wheel 11 engaged by a segmental

member 12 toothed to fit the teeth of the ratchet wheel and having its upper end engaged by the piston 9, so that the oscillation of the piston rocks the member 12 back and forth and causes a step-by-step rotation of 60 the ratchet wheel 11 and the chuck 8 upon which it is mounted. This mechanism for securing the step-by-step rotation of the chuck and drill steel is shown, described and claimed in my co-pending application Serial 65 No. 784,359, filed August 12, 1913, and no detailed explanation or claim with respect to this structure is therefore made in the present application.

The hammer piston 2 is controlled from 70 the valve 5 which reciprocates and alternately admits pressure to the opposite ends of the piston hammer to secure its reciprocation. Substantially the same valve mechanism and arrangement of ports for securing 75 the reciprocation of the hammer piston is disclosed in the patent to Richards No. 929,111, of July 27th, 1909, and no claim is made for this specific mechanism or arrangement of ports. In view of the fact 80 that this mechanism is a part of the prior art and fully disclosed in the patent to Richards, only sufficient explanation of such mechanism will be made in the present application as is necessary to an understanding 85 of my invention and improvement to be later explained. The relation of the valve 5 and hammer piston 2 will be most readily understood by a brief description of their 90 operation. When the valve 5 and hammer piston are in the position indicated in Fig. 1, fluid pressure from the throttle valve 6 is admitted through the passage 12, passes through the passage 13 in the plug 14, and thence through the inclined passage 15 to 95 the groove 16 in the valve cylinder, thence to the groove 17, and finally to the front side of the hammer piston 2 via the passage 18. At this time pressure is being supplied to the chambers 19 and 20 at opposite ends 100 of the valve 5, through the passages 21 and 22, the pressure in the chamber 19 being greater than that in the chamber 20 by reason of the fact that the passage 21 is larger than the end of the passage 22 leading into 105 the chamber 20, there being a constant discharge from each of the chambers through the small passages indicated at the upper sides of the chambers.

When the piston 2 moves to the rear as 110

indicated in Fig. 2, it covers the ends of the passage 21 and the groove 22. The covering of the end of the passage 21 cuts off the supply of pressure to the chamber 19 at the end of 5 the valve 5, so that the pressure drops in this chamber, while the covering of the groove 22 causes an increase in the chamber 20, such increase being due to the fact that the groove is supplied with air from the inclined passage 15, by means of the passage 23. The valve 5 is thus moved to the left to the position indicated in Fig. 2. This movement to the left of course cuts off the supply of air through the passage 18 and 10 permits a supply of air from the inclined passage 15 to the left hand end of the hammer piston, via the groove 24 and passage 25, so that pressure is applied to move the piston to the right. The movement of the 15 piston to the position indicated in Fig. 2 uncovers the end of the exhaust passage 26, such exhaust passage leading to the rear end of the machine and having its rear end open in the normal operation of the apparatus.

25 The throttle valve 6 as illustrated in Fig. 3 consists in a hollow tapered plug held upon its seat by the air pressure, and provided with a handle 27. A ball 28 fits in recesses in the plate 29 carried by the handle, and 30 serves to maintain the valve yieldingly in the various positions to which it is turned, the ball 8 being springheld as illustrated, and constituting a construction well known in the art.

35 The throttle valve has three different positions of use, such positions being illustrated in Figs. 4, 5, and 6. In order to lead to a clearer understanding of the structure the showing in Figs. 4, 5, and 6 is somewhat 40 diagrammatic, the various passages being placed all in the same plane, and in some cases being somewhat displaced from their actual positions in the machine, in order not to overlap and cause confusion. Referring first to the passages leading from the 45 valve 6 as shown in Figs. 4, 5, and 6, 12 is the passage heretofore referred to, leading to the valve 5 and serving to supply fluid for operating the piston hammer; 30 is the passage leading to the mechanism for rotating 50 the chuck and drill steel and including the piston 9 and valve 10 (see Fig. 1); 26 is the exhaust passage leading from the front end of the cylinder and heretofore referred to; 55 and 31 is a passage leading to the chamber 19 at the left hand end of the valve 5 (Fig. 1). The introduction of this passage 31 constitutes one of the features of my invention, and when air is admitted through this 60 passage 31 to the chamber 19 the valve 5 held in its right hand position as indicated in Fig. 1, thus permitting a constant supply of air through the passage 18 to the front end of the piston hammer 2, so that such 65 piston hammer is held in its position at the

left hand end of the cylinder until the passage 31 is cut off from its supply of air.

The valve 6 occupies the position indicated at Fig. 4, when the machine is first started. At this time the passage 32 through 70 the center of the plug which is supplied with air, is in communication with the passage 30 by reason of the passage or port 33, while a small amount of opening is secured between the passage 34 and the passage 12. At 75 the same time the exhaust passage 26 is placed in free communication with the outer air, by reason of the passages 35 and 36. At this time the machine runs "light". Sufficient air passes from the passage 34 to the 80 passage 12 to operate the hammer piston 2 lightly, and air supplied through the passage 30 serves to actuate the piston 9 and give the chuck 8 and drill steel 7 their step-by-step rotation.

If now it is desired to stop the operation of the hammer piston while still permitting the drill rotating mechanism to operate, and while permitting a flow of air through the drill steel the valve is moved to the 90 position indicated in Fig. 5. This movement permits of a full supply of air to flow to the passage 12, but at the same time the passage 37 is brought into communication with the passage 31, and the air supplied 95 to the chamber 19 in the valve cylinder serves to hold the valve in the position indicated in Fig. 1. When the valve is in this position the air supplied through the inclined passage 15 passes to the front end 100 of the cylinder by way of the grooves 16 and 17 and the passage 18. This supply of air serves to hold the hammer piston in its left hand position, and the air thus supplied into the cylinder from the passage 18 is 105 discharged through the passages 38 and 39 in the anvil and drill steel respectively, such draft of air serving to blow away the dust which accumulates in the drilling operation. Referring again to Fig. 5, it will be noted 110 that when the valve is in the position illustrated the passage 35 is out of registration with the ends of the passages 26 and 36, so that the exhaust passage 26 is closed at its rear end. This is an obviously desirable arrangement, as otherwise a part of the air supplied to the front end of the cylinder would discharge through this passage instead of discharging through the passages 38 and 39 in the anvil and drill steel. It 115 will also be noted that in the position indicated in Fig. 5 the air is still supplied from the throttle valve to the passage 30, so that the drill rotating mechanism continues to operate.

When it is desired to operate the mechanism at full speed the valve 6 is moved to the position indicated in Fig. 6. When the valve is in this position the end of the passage 31 is blanked, while the end of the ex- 120 125 130

haust passage 26 is connected to the passage 36 by means of the passage 40. At this time the full supply of air is directed to the passage 12, and to the passage 30, so that the 5 drill rotating mechanism and the hammer piston are operated at full speed. It will be seen from the foregoing that by the provision of the passage 31 controlled by the throttle valve and by the provision of the 10 means for controlling the exhaust from the throttle valve a very convenient method of operation is secured, since in order to stop the operation of the hammer piston while still continuing the operation of the drill 15 rotating mechanism and the supply of air through the drill steel, it is only necessary to move the valve to the position indicated in Fig. 5, at which time a full supply of air is directed through the 20 drill steel. When it is desired to stop all flow of fluid through the throttle valve it is rotated slightly counter clockwise from the position of Fig. 4, this blanking the ends 25 of the passages 12 and 30. The one movement of the throttle valve secures the stopping of the hammer piston, the closing of the exhaust, and consequently a full supply 30 of air at maximum pressure through the drill steel, thus insuring economy of air and 35 an effective cleaning of the hole being drilled.

The arrangement of the ports and passages as illustrated in Figs. 4, 5, and 6, is merely one of a number which might be 5 made for securing the same results, the invention being directed broadly to the provision of means whereby the movement of the throttle valve stops the movement of the main valve and preferably at the same time blanks 10 the exhaust. The invention is not limited to the type of valve 5, but contemplates any valve having a back-and-forth movement, and further contemplates the use of any and all means whereby unbalanced pressure is secured upon the pressure receiving surfaces of the valve to stop it continuously in one 15 position. Furthermore the invention is not limited to the use of a fluid pressure means for securing the stoppage of the main valve by a movement of the throttle valve, but 20 contemplates any and all kinds of connections—fluid and otherwise—whereby the movement of the throttle valve to one position stops the main valve in one extreme, 25 while permitting a flow of fluid pressure to one end of the hammer piston. The invention is also applicable to other kinds of machines.

What I claim is—

1. In combination in a fluid-actuated machine, a hammer piston, a fluid-operated main valve movable back and forth and controlling the admission of fluid pressure alternately to the two ends of the hammer piston, a throttle valve controlling the ad-

mission of fluid pressure to the machine, and connections whereby the movement of the throttle valve secures the stopping of the said main valve in one extreme of movement while fluid pressure is admitted past the 70 throttle to one end of the hammer piston.

2. In combination in a fluid-actuated machine, a hammer piston, a main valve movable back and forth and provided with a pair of pressure receiving surfaces to move the 75 valve in opposite directions and arranged to admit fluid pressure alternately to the two ends of the hammer piston, a throttle valve controlling the admission of fluid pressure to the machine, and means controlled by the 80 throttle valve when in one position whereby the fluid pressure upon the two pressure receiving surfaces is unbalanced and the main valve held continuously in one extreme of movement, while fluid pressure is continuously applied to one end of the hammer 85 piston.

3. In combination in a fluid-actuated machine, a hammer piston, a main valve movable back and forth and provided with a 90 pair of pressure receiving surfaces to move the valve in opposite directions and arranged to admit fluid pressure alternately to the two ends of the hammer piston, a throttle valve controlling the admission of 95 fluid pressure to the machine, and connecting passages controlled by the throttle valve for securing continuous balanced pressure upon the said pressure receiving surfaces and preventing the movement of the main 100 valve from one extreme of movement while fluid pressure is supplied past the throttle valve to one end of the piston hammer.

4. In combination in a fluid-actuated machine, a hammer piston, a main valve movable back and forth for controlling the movements of the hammer piston provided with a pair of pressure receiving surfaces to move it in opposite directions and arranged so that the application of pressure to such surfaces is controlled by the hammer piston, and a throttle valve controlling the admission of fluid pressure to the machine and arranged in one position to permit the constant supply of fluid pressure to one of the 110 said pressure receiving surfaces and stop the operation of the main valve and the hammer 115 piston.

5. In a fluid-actuated drilling machine provided with a cylinder and hollow drill 120 steel, a hammer piston, a main fluid-operated valve for controlling the movements of the hammer piston provided with a pair of pressure receiving surfaces to move it in opposite directions, and arranged so that the application of pressure to such surfaces is controlled by the hammer piston, and a 125 throttle valve adapted in one position to admit fluid pressure continually through the machine and the hollow drill steel and also 130

arranged so that while maintained in such position the pressure receiving surfaces of the main valve are exposed to unbalanced fluid pressure to stop the movement of such valve in one extreme of movement and of the hammer piston.

6. In a fluid-actuated drill machine provided with a cylinder and hollow drill steel with its passage communicating with the front end of the cylinder, a main valve movable back and forth and arranged in one position to admit fluid pressure to one end of the cylinder and in its other position to admit fluid pressure to the other end of the cylinder, the said valve having a pair of pressure receiving surfaces to move it in opposite directions, and a throttle valve arranged so that when in one position fluid pressure is admitted to one of the said pressure-receiving surfaces to hold the main valve in one extreme of movement, and simultaneously fluid pressure is admitted past the main valve to the front end of the cylinder and through the hollow drill steel.
7. In a fluid-actuated drilling machine provided with a cylinder and hollow drill steel with its passage communicating with the front end of the cylinder, a main valve movable back and forth and arranged in one position to admit fluid pressure to one end of the cylinder and in its other position to admit fluid pressure to the other end of the cylinder, the said valve having a pair of pressure receiving surfaces to move it in opposite directions, an exhaust passage leading from the front end of the cylinder to the rear portion of the machine, and a throttle valve arranged so that when in one position it (1) closes the said exhaust passage, (2) admits a constant supply of fluid pressure to one of the said pressure receiving surfaces thus holding the main valve in one extreme of movement and stopping the movement of the hammer piston, and (3) admits fluid pressure past the main valve to the front end of the cylinder and through the hollow drill steel.

8. In a fluid-actuated drilling machine provided with a cylinder and a hollow drill steel with its passage communicating with the front end of the cylinder, a fluid-operated means for rotating the drill steel, a hammer piston, a main valve movable back and forth and arranged in one position to admit fluid pressure to one end of the cylinder and in its other position to admit fluid pressure to the other end of the cylinder, the said valve having a pair of pressure receiving surfaces to move it in opposite directions, a supply passage leading to the said fluid-operated rotating means, an exhaust leading from the front end of the cylinder, and a throttle valve arranged so that in one position it (1) opens the said supply passage, (2) closes the said exhaust passage,

(3) admits a constant supply of fluid pressure to one of the said pressure receiving surfaces, thus holding the main valve in one extreme of movement and stopping the movement of the hammer piston, and (4) admits fluid pressure past the main valve to the front end of the cylinder and through the hollow drill steel.

9. In combination in a drilling machine, a cylinder, a hollow drill steel, a hammer piston, a main valve for controlling the admission of fluid pressure alternately to the two ends of the hammer piston, an exhaust passage, and a throttle valve, the said throttle valve in one position admitting fluid to operate the main valve and hammer piston with the exhaust passage uncovered, and in another position closing the exhaust, admitting fluid pressure continuously to one end of the main valve to stop the movement of such valve and permitting fluid pressure to flow continuously through the cylinder and hollow drill steel.

10. In combination in a fluid actuated machine, a hammer piston, a throttle valve controlling the admission of fluid pressure to the machine, a fluid operated automatic valve controlling the operation of the hammer piston, and connections whereby the movement of the throttle valve secures the stopping of the said automatic valve and the piston in one extreme of movement.

11. In combination in a fluid actuated machine, a hammer piston, a throttle valve controlling the admission of fluid pressure to the machine, a fluid operated automatic valve controlling the operation of the hammer piston, and connections whereby the movement of the throttle valve secures the stopping of the said automatic valve and the piston in one extreme of movement, while fluid pressure is admitted past the throttle to one end of the hammer cylinder.

12. In combination in a fluid actuated machine having a cylinder provided with an exhaust passage and a hollow drill steel with its passage in communication with the said cylinder, a hammer piston, a throttle valve controlling the admission of fluid pressure to the machine, connections whereby the movement of the throttle valve secures the stopping of the piston in one extreme of movement while admitting fluid pressure to the cylinder and through the drill steel, the throttle valve being arranged when in such position to close the said exhaust passage.

13. In combination in a fluid actuated machine having a cylinder provided with an exhaust passage and a hollow drill steel with its passage in communication with the said cylinder, a hammer piston, fluid-operated means for rotating the drill steel, connections for supplying fluid pressure to the cylinder and drill rotating means, and

means for simultaneously closing the exhaust and stopping the movement of the hammer piston, while permitting the passage of fluid to operate the drill rotating means and while permitting the passage of fluid to the cylinder and through the drill steel.

In testimony whereof I have hereunto signed my name in the presence of the two subscribed witnesses.

LOUIS W. GREVE.
